HOSE CABINET

Aneal C. Angelillo, Long Island City, N. Y.

Application June 19, 1952, Serial No. 294,419

6 Claims. (Cl. 312—290)

1

This invention relates to a hose cabinet for use with washing machines.

It is an object of the present invention to provide a hose cabinet whereby the hose which is extended from a washing machine can be enclosed when not in use in a cabinet beside the washing machine and wherein the hose can be readily removed from the cabinet at times when the washing machine is to be connected to the water spigots upon the sink and the drain hose for the washing machine extended to the sink.

It is another object of the invention to provide in a hose cabinet adapted to enclose the hose of a washing machine, a soap supporting member which is adjustable in and out of the top of the hose cabinet and which when being depressed into the hose cabinet will serve to pull inwardly the hose and confine it to the cabinet and whereby upon operation of a release catch the soap tray can be returned to the top of the cabinet to expose its contents.

It is another object of the invention to provide a hose cabinet with mechanism for pulling the hose into the cabinet and which upon being released will extend the hose out of the cabinet and wherein the release of the hose is effected upon first opening the doors of the cabinet and then by depressing a foot lever.

Other objects of the invention are to provide a hose cabinet for use with washing machines to confine the loose hose when not in use and having the above objects in mind, which is of simple construction, inexpensive to manufacture, has a minimum number of parts, of pleasing appearance, compact and efficient in operation.

For other objects and for a better understanding of the invention, reference may be had to the following detailed description taken in connection with the accompanying drawing, in which:

Figure 1 is a perspective view of the cabinet, constructed according to one form of the invention with the front and top doors open, the soap tray extended to an elevated position and the side of the cabinet broken away to show the hose support;

Fig. 2 is a fragmentary, vertical sectional view taken on line 2—2 of Fig. 1 and showing the soap tray mechanism;

Fig. 3 is an enlarged fragmentary sectional view taken on line 3—3 in Fig. 1 and through the roller element on the upper end of the hose;

Fig. 4 is an elevational view of the roller bracket at the upper end of the hose support;

Fig. 5 is a perspective view of the hose cabinet 55

2

disposed beside the washing machine and with the hose extended from the cabinet and connected with the sink outlets and the drain hose extending from the washing machine to the sink;

5 Fig. 6 is a fragmentary vertical sectional view of the hose cabinet according to a modified form of the invention and showing a common mechanism for thrusting outwardly the hose and releasing of the soap tray;

10 Fig. 7 is a perspective view of the hose operating arm used in the form of the invention shown in Fig. 6;

15 Fig. 8 is a fragmentary vertical sectional view taken on line 8—8 of Fig. 6 and through the soap tray mechanism thereof.

Referring now particularly to Figs. 1 to 4, inclusive, 10 and 11 represent respectively spaced side portions which are connected together at the rear of the cabinet by a back portion 12. The side portions provide openings at the front and top of the cabinet. The front opening is covered by a door 13 supported on hinges 14 and 15 and which has a fitting 16 connected to the inner side thereof over which the hose can be extended. At the top of the door 13 is another fitting or hook 17 by which the hose can be retained.

Adapted to extend over the top opening is a top door 18 connected to the top edge of side portion 11 by hinges 19 and 21 and also having a hook fitting 22 for retaining the hose secured on the forward underside of the top door.

Connected between the side portions is a bent channel member 23 having a vertically extending portion 24, and a horizontally extending bottom portion 25. The flanges of this channel member are connected to the side portions 10 and 11 by screws 26. The upper end of the vertical portion 24 is rounded and has a roller bracket 27 between which the roller 28 is journaled. This roller 28 is grooved to receive hoses 29 and 30. The bracket 27 is made secure to the bent upper end of the hose supporting member 23 by fastening bolts 31. In the rear of the cabinet is a soap tray device 33 which is lowered when the cabinet doors are closed and which is released by a button 58 to return the same to the raised position to make soap articles 34 accessible. This soap tray device comprises a main support plate 35 having downwardly turned ends 36 and 37. These ends are guided in angle section guide members 38 which are disposed on the side portions 10 and 11 of the cabinet with one guide 38 being at each corner of the plate 35.

On the top of the plate is a tray 39 having

upstanding sides pivotable about a rivet 40 to the plate 35 so that when the plate 35 is elevated, the tray 39 can be swung outwardly to make more available the contents of the tray, in the manner as shown in Fig. 1.

Connected to the bottom face of the plate 35 by members 42 which are in turn welded to the underside of the plate 35 is an air cylinder 43 in which is disposed a piston structure 44 having a piston rod 44' that is fixed to the bracket 46 extending inwardly from the rear portion 12. On the lower end of the cylinder 43 is a lug 47 to which a wire 48 is connected. This wire extends over a pulley 49 and is connected to a tension spring 51. The tension spring 51 is in turn connected to a lug 52 on the bracket 46. The air cylinder 43 has a hole 53 in its upper end and a hole 54 at its lower end through which the rod 44' can slide. When it is desired to withdraw the soap device into the cabinet, the tray 39 is turned inwardly and the soap device is depressed and moved downwardly against the action of the spring 51 and to a position shown in dot and dash lines in Fig. 2 where it will be retained by a spring latch lever 55 against the action of spring 51. This lever 55 is pivoted on a lug 56 on the rear portion 12 and is normally urged inwardly at its lower end by a compression spring 57. A button 58 is slidable in the upper end of the portion 12 and can bear against the lever 55 in order to release the soap device and permit the upward movement by the action of the spring 51. The air passing through the openings 53 and 54 in the cylinder 43 will cushion and prevent breakage of the device.

As shown in Fig. 5, one hose 29 is connected to the water spigot having a mixing chamber as shown at 61. This water spigot has two valves 62 and 63 for controlling respectively the hot and cold water. In this Fig. 5 there is shown a modified form of the invention but the same hose is extended in a similar manner to the form of the invention shown in Fig. 1. The other hose 30 is for drainage water and is connected to an outlet of washing machine 64. These hoses 29 and 30 extend through a recess 65 in the side portion 30 and are pulled in by connection with the hooks 10 and 66 and 66' on the soap display device plate 35. As this plate is retracted and pulled down, the hose is taken in double and is drawn inwardly over the roller 23 and upwardly along the channel guide 24. It is only necessary for the hose connections to be taken from the tub 67 doubled over and then placed upon the hooks 65 and 66 and thereafter forcing downwardly the soap tray device. The free ends of the hoses 29 and 30 will lie at the front of the cabinet. The doors 13 and 18 are closed and the hose will thus be confined within this hose cabinet.

In the form of the invention shown in Figs. 5 to 8, the channel guide can be extended out of the hose cabinet and in a manner to remove the hose from the cabinet so that it will be more accessible. This same channel guide has a projection on it to hold down the soap tray device. According to this form of the invention the same shaped cabinet is used. This cabinet comprises side portions 10 and 11 and a rear portion 72. A top cover 73 provides access to the top of the cabinet, and a front cover 73' when opened provides access to the front of the cabinet by which the hoses can be made readily accessible.

A soap tray plate 75 is adjustable in guides 76. This plate 75 is supported on a cylinder 77 which

contains a piston structure similar to that shown in Fig. 2 and which has a piston rod 78 that is supported on the bracket 79. A wire 81 is connected to a lug 82 at the lower end of the cylinder 77 and this wire 81 in turn passes over a pulley 83 and is in turn connected to a tension spring 84 that is in turn connected to a lug 85 on the bracket 79. This tension spring urges upwardly the soap tray plate 75. A soap tray 86 is pivoted on the top of the plate 75 and in the same manner as shown in Fig. 1, and can be pivoted outwardly from the top of the plate when the plate is elevated. Extending laterally from the cylinder 77 is a press button 87 that can be depressed to move downwardly the soap tray. This press button arm 87 extends outwardly through the vertically extending slot 88 in the side portion 71. The cylinder 77 has a bracket 90 on which is pivoted a latch 91 adapted for engagement with a long latch arm 92 extending rearwardly from a pivoted guide channel 93 which is pivoted between the side portions 71 and 79 by a pivot pin 94.

The upper end of the channel guide 93 has a transverse roller 95 over which the hose connections 29 and 30 are extended.

Within the cabinet and pivoted between the sides thereof at 96 is a pull down arm 97 having an elongated slot 98 through which the pin 99 extends. The outer end of the pull down arm 97 has clips 101 and 102 for receiving the hose connections 29 and 30.

As the soap tray device is depressed by the button 87, the arm 97 is brought down and the hose connections fastened to the end of the arm 97 will be brought inwardly therewith.

Depending from the channel guide 93 is a link 104 which is connected to a foot lever 105 pivoted to the side portions of the cabinet at 106 at the bottom thereof. A tension spring 107 is connected to the lever 105 to a stop or anchor pin 108.

Extending horizontally from the channel guide 93 is a support 109 for supporting the hose pieces in the cabinet once they are pushed and pulled thereinto.

In order to gain access to the hose connections, the door 73' is opened so that the top cover 73 may be lifted. The housewife will then step upon the foot lever 105 to pivot outwardly and downwardly the channel guide 93. This downward movement of the lever 105 is against the action of the spring 107 at the same time the arm 92 will be released from the latch 91 and the soap tray device will be elevated by the tension spring 84 so that the arm 97 pivotally connected to the bracket 93 on the air cylinder 77 will be lifted to a raised position as shown in dot and dash lines so that a long length of the hose will be elevated and the channel guide 93 will thrust forwardly the hose sections so that they can be easily grasped by the housewife to pull them outwardly for connection with the sink 67 and the spigots 62 and 63.

Upon release of the foot lever 105, the spring 107 will thrust rod 104 upwardly and accordingly pivot inwardly the channel guide 93. Thereafter the door 73' can be closed.

While various changes may be made in the detail construction, it shall be understood that these changes shall be within the spirit and scope of the present invention as defined by the appended claims:

What is claimed is:

1. A hose cabinet comprising side portions and a rear portion, a channel guide vertically disposed

between the side portions, a roller bracket connected to the upper end of the channel guide and having a roller over which the hose can be extended, a front door element hinged to one of the side portions to close the front opening, a door on top connected to one of the side portions on top thereof to close the top opening.

2. A hose cabinet comprising; side portions and a rear portion, a hose guide member pivotally connected between the side portions and extending vertically upwardly over which hose pieces can be extended and guide, an elevatable device disposed between said side portions, spring means to urge the movement of the elevatable device to the raised position, catch arm means extending from the elevatable device, arm means engaging with the catch arm means on the elevatable device, and lever means connected to the guide member for releasing the arm means on the guide member from the catch arm means of the elevatable device.

3. A hose cabinet having spaced sidewalls, a rear wall, and a front door vertically hinged to one of the side walls, one of said sidewalls having an opening therein to pass a hose therethrough, a vertically extending hose guide disposed between the sidewalls accessible from the front of the cabinet, and a grooved guide roller journaled on said hose guide to receive and support a hose thereon.

4. A hose cabinet having spaced sidewalls, a rear wall, and a front door vertically hinged to one of the sidewalls, one of said sidewalls having an opening therein to pass a hose therethrough, a vertically extending hose guide disposed between the sidewalls accessible from the front of the cabinet through the front door, a grooved guide roller journaled on said hose guide to receive a hose thereon; and a top cover hinged to the top of one of the sidewalls and adapted to extend over the opening in the top of the cabinet.

5. A hose cabinet having spaced vertical sidewalls, a rear wall, and a front door hinged to one

of the sidewalls, one of said sidewalls having an opening therein to pass a hose therethrough, a channelled guide extending vertically between the sidewalls, said front door pivotable to provide access to the vertically extendable channel guide, a guided retractable stand with means urging its upward movement between the sidewalls, releasable means for holding the retractable stand in the downward position, said retractable stand having means thereon for receiving hose pieces for drawing the same substantially inwardly as the stand is depressed.

6. A hose cabinet comprising; side portions and a rear portion, a hose guide member pivotally connected between the side portions and extending vertically upwardly over which hose pieces can be extended and guided, an elevatable tray disposed between said side portions, a cylinder affixed between said elevatable tray, a piston movable within said cylinder, spring means cooperatively engaging the cylinder and secured to the cabinet to urge the movement of the elevatable tray to be raised, catch arm means extending from the cylinder on the elevatable tray, arm means extending from the guide member and extending to engage the catch arm means on the elevatable tray, and lever means connected to the guide member for releasing the arm means on the guide member from the catch arm means of the elevatable tray.
